MACHINE FOR APPLYING PRESSURE TO
SHOE BOTTOMS

Charles J. Gross, Melrose, Mass., assignor to
United Shoe Machinery Corporation, Borough
of Flemington, N. J., a corporation of New
Jersey

Application January 13, 1940, Serial No. 313,712

16 Claims. (Cl. 12—33)

This invention relates to machines for use in the manufacture of shoes and is illustrated herein as embodied in a machine for applying pressure to shoe bottoms.

One well-known type of machine for use in applying pressure to shoe bottoms is illustrated in Letters Patent of the United States 2,047,185 granted July 14, 1936, on an application of M. H. Ballard et al. In machines of this type a pad is provided for supporting a sole and shoe during the pressing operation. A swingable frame carries toe and heel abutments for engaging the toe portion of the shoe and the cone of the last respectively, the toe and heel abutments being carried by arms which are mounted on vertically slidable rods in the swingable frame. Prior to a pressing operation, the frame is in a position rearward of the pad to facilitate the positioning of the shoe and sole thereon. The frame is then swung manually to a position in which the toe and heel abutments are directly over the shoe and pressure is then applied to the arms carrying the abutments to press the shoe against the sole supported on the pad. The toe and heel abutments are arranged to occupy positions slightly above the toe portion of the shoe and the cone of the last respectively prior to the application of pressure to the arms upon which they are carried.

While machines of the type illustrated in this patent are well adapted for use on low shoes, some difficulty has been experienced when operating on high shoes such as men's work shoes. The uppers of these shoes extend a considerable distance above the cone of the last so that it is generally necessary for the operator to hold the upper outward and downward away from the cone of the last as the swingable frame is moved to a position in which the heel abutment is directly over the cone to prevent interference between this abutment and the upper. This operation of holding the upper out of the path of movement of the heel abutment during the forward swinging movement of the frame requires a certain amount of additional effort on the part of the operator which is avoided by the use of a machine embodying the principles of the present invention.

One of the objects of the present invention is the provision of a machine for applying pressure to shoe bottoms wherein the machine is equally well adapted for use with high or low shoes and in which danger of interference between the upper and the pressure applying means when a high shoe is being acted upon is greatly reduced.

In accordance with the present invention, the heel abutment through which pressure is applied to the cone of the last is mounted for vertical movement with respect to the vertically movable arm by which it is supported. This arm is spring biased vertically upward to such a height that there will be no interference between the heel abutment and the upper as the frame is swung forwardly to position the abutments over the shoe. The heel abutment is then moved downwardly with respect to the arm by which it is supported, by the operator, until it is in proximity to the cone of the last. The vertical movement of the heel abutment to this position may be effected without any danger of engaging the upper of the shoe. Pressure is then applied to the arms carrying the heel and toe abutments to press the shoe against the sole supported on the pad. During the initial part of the pressure-applying movement of the arm carrying the heel abutment, a pawl is operated to lock the heel abutment against vertical movement with respect to the arm by which it is carried so that it will not be moved upwardly by its spring. Upon release of the pressure, the arms carrying the abutments move upwardly with respect to the swinging frame and the pad under the influence of a pair of springs and after the arm carrying the heel abutment has moved to its uppermost position, the aforementioned pawl is released to permit further upward movement of the heel abutment with respect to its supporting arm, thus carrying the heel abutment vertically above the top of the upper. The swingable frame may now move rearwardly without interference between the heel abutment and the upper so that the shoe may be removed from the pad and another shoe and sole placed thereon. The provision of a pawl operated in the manner described above forms another feature of the present invention.

In accordance with a further feature of the present invention, the means by which downward movement is imparted to the heel abutment with respect to its supporting arm is located in close proximity to a handle attached to the swinging frame so that the operator, by grasping this handle, may swing the frame forwardly and with his thumb may then move the heel abutment downwardly while holding the frame in its forward position so that both of these operations may be carried out by the use of one hand.

These and other features of the invention will now be described in detail in the specification and illustrated in the accompanying drawings, in which—

Fig. 1 is a front elevation of a portion of one form of machine embodying the principles of the present invention;

Fig. 2 is a sectional view taken on the line II—II of Fig. 1;

Fig. 3 is a side elevation of the machine illustrated in Fig. 1;

Fig. 4 is a rear view of a part of the mechanism illustrated in Fig. 1, showing the hydraulic cylinder and the connections to the arms carrying the heel and toe abutments;

Fig. 5 is a plan view of the machine shown in Fig. 1;

Fig. 6 is a sectional view taken on the line VI—VI of Fig. 5; and

Fig. 7 is a sectional view taken on the line VII—VII of Fig. 5.

A pad box provided with gage mechanism for properly positioning a shoe and sole on the pad similar to that illustrated in Letters Patent of the United States No. 2,145,265, granted January 31, 1939, on an application of L. G. Knowles is represented generally by the reference character 10. Located rearwardly of the pad box is a hydraulic cylinder 12 (Figs. 3 and 4) by means of which pressure is applied to the shoe to press the same against the sole supported on the pad by mechanism to be described. A pressure distributing device 14 (Fig. 4) is connected to a piston 16 in the cylinder 12, this pressure distributing device operating to cause equal pressures to be applied to the forepart of the shoe and the cone of the last as described in the Ballard et al. patent.

The pressure distributing device 14 includes an equalizer lever 17 provided at the opposite ends thereof with spherical bearings 18 and 20. Surrounding the bearings 18 and 20 are the forked ends of arms 22 and 24, respectively, the lower ends of these arms being provided with straps 26 and 28 underlying the bearings 18 and 20 and securing the arms thereto. The upper ends of the arms 22 and 24 are similarly connected to bearings 30 and 32 mounted in the forked rearward ends of levers 36 and 38. The levers 36 and 38 are fulcrumed on a shaft 40 (Figs. 1 and 3) which is in turn mounted in vertical arms 42 and 44 pivotally connected at 46 to the frame of the machine. These arms are movable from the full line position to the broken line position of Fig. 3, their movement being limited by means of a rod 48 carried by them and slidable through a lug 50 carried by the side of the cylinder 12. Nuts 52 and 54 carried by the rod 48 on opposite sides of the lug 50 cooperate therewith to limit the movements of the arms 42 and 44 about the pivot 46.

A crosshead 56 is connected to the upper ends of the arms 42 and 44 and provides bearings for the upper ends of vertically slidable shafts 60, 62. The lower ends of these shafts are slidably mounted in a second crosshead 64 (Fig. 3) carried by the lower ends of the arms 42 and 44. The arms 42 and 44 and the crossheads form a swingable frame by means of which the heel and toe abutments are supported in a manner to be described. Screws 66 carried by the crosshead 56 cooperate with the levers 36 and 38 adjustably to limit clockwise movement of these levers about the shaft 40. Movement of the levers in the opposite direction is adjustably limited by means of screws 68 carried by the crosshead 56.

The forward end of the lever 36 is pivotally connected to the upper part of a frame member

70, the rearward part of which is secured to the rod 62. A spring 71 (Fig. 1) surrounding the rod 62 acts between the lower crosshead 64 and the lower rearward part of the frame member 70 to urge this member and the rod 62 upwardly. A T-slot 72 formed in the lower part of the frame member 70 forms a way for a slide member 74 carrying a toe abutment 76. The slide 74 is connected by means of a bell crank lever 78 pivoted at 80 to the lower part of the frame member 70 to a link 82 which is in turn connected to an arm 84 movable with a handle 86. The handle 86 is mounted for pivotal movement about a shaft 88 (Fig. 1) in the end of an arm 90 fixed to the rod 60. This handle serves as means for adjusting the toe abutment 76 longitudinally of the pad box by pivotal movement of the handle and also serves to enable pivotal movement of the arms 42 and 44 about the pivot 46 by the operator.

An arm 94 is secured to the rod 60, the forward end of this arm being fastened by a pin and slot connection to the forward end of the lever 38. This rod 60 is urged upwardly by means of a spring 96 acting between the crosshead 64 and the arm 90 fixed to the rod 60. The forward end of the arm 94 is provided with a T-slot 98 forming a guideway for a slide 100 for permitting adjustment of this slide longitudinally of the pad box. A rod 102 is carried for vertical sliding movement by the slide 100, the downward movement of the rod 102 with respect to the slide being limited by a collar 104 which is arranged to engage the upper end of the arm 94 upon sufficient downward movement of the rod with respect thereto. The collar 104 is adjustably connected to the upper end of the rod 102 by means of a screw 106 arranged to engage any one of a plurality of circular recesses 108 arranged in the upper part of the rod. The rod 102 is urged upwardly with respect to the slide 100 by means of a spring 110 the upper end of which is connected to the horizontally extending portion of an arm 112, the lower end of this arm being mounted in a laterally extending portion of the slide 100. The lower end of the spring is connected to the bottom of a bore extending partially through the rod 102. Upward movement of the rod 102 with respect to the slide 100 is limited by means of a member 114 (Figs. 6 and 7) mounted on the lower end of the rod and engaging the under side of the slide 100 upon sufficient upward movement of the rod 102. The member 114 includes a pair of spaced depending arms 116 between which is pivotally connected a heel abutment 118 which is, in fact, arranged to engage the cone of a last. Springs 120 positioned between the heel abutment 118 and the member 114 act to maintain the lower surface of the heel abutment in a horizontal position while permitting pivotal movement of the heel abutment with respect to the member 114.

The rear side of the rod 102 is provided with rack teeth 121 with which engage the teeth of a gear 122 mounted for rotation in the slide 100. A gear 124 (Fig. 3) fast with the gear 122 meshes with the teeth of a rack member 126 arranged for horizontal sliding movement in the lower portion of the slide 100. The rearward end of the rack member 126 has connected thereto a laterally extending arm 128 to which is connected an arm 130 extending forwardly of the machine and terminating in a thumb piece 132. A cover member 134 attached to the slide 100

encloses the gear 124 and most of the rack member 126. Upon sliding movement of the rack 126 with respect to the slide 100, the gear 124 is rotated which in turn causes rotation of the gear 122 and vertical movement of the rod 102 carrying the heel abutment 118. If the rack member 126 is moved rearwardly, the rod 102 is moved downwardly against the force of the spring 110 tending to move the rod 102 upwardly. The thumb piece 132, by means of which motion is imparted to the rack member 126, is positioned adjacent to the handle 86 and is arranged to be actuated by the thumb of the right-hand of the operator, the fingers of which are simultaneously grasping the handle 86 to hold the arms 42 and 44 in their forward or full line positions (Fig. 3).

The rod 102 is also provided with ratchet teeth 140 (Figs. 1 and 7) which are arranged to be engaged by a pawl 142 pivoted to the slide 100 for holding the rod 102 in its downward position with respect to the slide against the force of the spring 110. The pawl is pinned to a horizontally extending shaft 144 which projects from the slide 100 and carries at its outer end an arm 146 which is urged in a counter-clockwise direction, as viewed in Fig. 1, by means of a compression spring 148 engaging the under side of the arm 146, the lower end of which spring is seated in a recess of a projection 150 on the forward part of the slide 100 (Fig. 6). The spring 148 acts to move the pawl 142 into engagement with the teeth 140 to prevent vertical movement of the rod 102 with respect to the slide member 100 under the influence of the spring 100.

A rod 154 (Figs. 1, 3 and 6) is carried for vertical movement in a forwardly projecting portion of the arm 94. A pin 156 carried by the rod 154 cooperates with a slot 158 in the front of the arm 94 for limiting vertical movements of the rod 154. A plate 160 carried by the lower end of the rod 154 is arranged to engage a forwardly projecting portion of the arm 146 for moving this arm in a direction to disengage the pawl 142 from the ratchet teeth 140 in the rod 102 upon downward movement of the rod 154 relative to the arm 94, or into the position illustrated in Fig. 6.

The crosshead 56 is provided with a forwardly extending arm 162 in the front end of which is threaded a screw 164, this screw being provided with a lock nut 166 for securing the screw 164 in adjusted position in the arm 162. The lower end of the screw 164 is arranged to engage the upper end of the rod 154 as the arm 94 carrying the slide 100 moves upwardly under the force of the spring 96 to the position illustrated in Figs. 3 and 6. As the arm moves upwardly, the upper end of the rod 154 is moved downwardly with respect thereto after the upper end thereof has engaged the screw 164. This downward movement of the rod 154 with respect to the arm 94 causes the pawl 142 to move into the position shown in Fig. 7 thus permitting vertical movement of the heel abutment carrying rod 102 relatively to the slide 100 under the force of the spring 110. As the arm 94 moves downwardly by reason of the movement imparted to the lever 38 by the piston 16 in the hydraulic cylinder 12, the upper end of the rod 154 moves away from the screw 164 whereupon the compression spring 148 moves the outer end of the arm 146 upwardly causing a similar movement to be imparted to the rod 154 and moving the 75

pawl 142 into locking engagement with the teeth 140 in the rod 102 to hold this rod in the position to which it has been moved by the operator against the force of the spring 110.

At the beginning of a pressing operation, the vertical arms 42 and 44 will be in their rearward positions as illustrated by the broken lines in Fig. 3 so that the heel and toe abutments and associated mechanism will be positioned rearwardly of the pad box 10. There is, accordingly, no interference from these parts to the proper positioning of the shoe and sole upon the pad box. After the shoe S (Fig. 1) having a last L therein and a sole have been properly positioned on the pad, the arms 42 and 44 are brought forwardly by the operator by moving the handle 86 so that the toe and heel abutments are positioned vertically over the shoe. At this time the toe and heel abutments will be substantially in the positions shown in Fig. 1 with the heel abutment above the heel portion of the upper so that there is no interference between this heel abutment and the upper as the heel abutment is moved to this position, even when the shoe supported on the pad is a high shoe as illustrated. Adjustment of the toe abutment lengthwise of the shoe may be effected by rocking the handle about the pivot 88. The operator keeps the fingers of his right hand on the handle 86 so that the arms 42 and 44 will be maintained in their vertical positions and, with the thumb of the same hand on the thumb piece 132, moves the rack member 126 rearwardly which causes downward movement of the rod 102 and with it the slide 100 and the heel abutment 118 until the collar 104, carried by the rod 102, engages the top of the arm 94. The collar 104 will preferably be adjusted on the rod 102 so that the rod will be moved downwardly with respect to the arm 94 the desired distance with the heel abutment adjacent to the cone of the last. The left hand of the operator is available at this time to spread the top of the upper slightly if necessary to prevent engagement of the heel abutment therewith but since the movement imparted to the heel abutment upon entering the upper is a vertical one, very little and in many cases no spreading of the upper by the operator will be required.

Power is now applied to the levers 36 and 38 to move the arms 92 and 94 downwardly to apply pressure to the shoe and the sole through the toe and heel abutments. Upon initial downward movement of the arm 94, the rod 154 moves away from the screw 164 so that the spring 148 is effective to move the pawl 142 into locking engagement with the heel abutment carrying rod 102 to lock this rod to the arm 94. Since a greater part of the downward movement of the heel abutment is effected manually, the piston 16 in the hydraulic cylinder 12 need not travel any farther than in a machine of the type shown in the Ballard et al. patent although interference between the top of the upper and the heel abutment during movement of this abutment forwardly from its rearward position is entirely eliminated.

At the conclusion of the pressing operation, the piston 16 moves downwardly in the cylinder 12, thus moving the levers 36 and 38 in a clockwise direction as viewed in Fig. 3 to permit upward movement of the arms 92 and 94 by their associated springs. After the arm 94 has moved up sufficiently, the rod 154 will engage the screw 164 and the arm will move upwardly with respect

thereto so that the pawl 142 is moved out of engagement with the ratchet teeth in the rod 102. The rod is now free to move upwardly with respect to the arm 94 under the force of the spring 110. The heel abutment will therefore move to a position above the top of the upper so that the arms 42 and 44 may move rearwardly carrying the toe and heel abutments with them without any interference between the heel abutment and the upper during this rearward movement.

Having thus described the invention, what I claim as new and desire to secure by Letters Patent of the United States is:

1. In a machine for applying pressure to shoe parts, a pad for supporting a sole against which a shoe is to be pressed, a member for pressing a shoe against a sole supported on said pad, a heel abutment slidably carried by said member for movement toward and away from said pad, means urging said heel abutment away from said pad, and means operative in response to movement of said member in pressure-applying direction for locking said heel abutment to said member for movement therewith.

2. In a machine for applying pressure to shoe parts, a pad for supporting a sole against which a shoe is to be pressed, a member for pressing a shoe against a sole supported on said pad, a heel abutment slidably carried by said member for movement toward and away from said pad, means operative in response to movement of said member in pressure-applying direction for locking said heel abutment to said member for movement therewith, and means for releasing said locking means in response to movement of said member in pressure-releasing direction.

3. In a machine for applying pressure to shoe parts, a pad for supporting a sole against which a shoe is to be pressed, a member for pressing a shoe against a sole supported on said pad, a heel abutment slidably carried by said member for movement toward and away from said pad, means for locking said heel abutment for movement with said member in pressure-applying direction, and means for releasing said locking means in response to movement of said member in pressure-releasing direction.

4. In a machine for applying pressure to shoe parts, a pad for supporting a heel against which a shoe is to be pressed, a member for pressing a shoe against a sole supported on said pad, a heel abutment slidably carried by said member for movement toward and away from said pad, a spring urging said heel abutment upwardly with respect to said pad and said member, means for locking said heel abutment to said member for movement therewith in pressure-applying direction, and means for releasing said locking means in response to movement of said member in pressure-releasing direction.

5. In a machine for applying pressure to shoe parts, a pad for supporting a sole against which a shoe is to be pressed, a member for pressing a shoe against a sole supported on said pad, a heel abutment slidably carried by said member for movement toward and away from said pad, means operative in response to movement of said member in pressure-applying direction for locking said heel abutment to said member for movement therewith, and a spring acting to move said heel abutment relative to said member away from said pad.

6. In a machine for applying pressure to shoe parts, a pad for supporting a sole against which a shoe is to be pressed, a member for pressing a

shoe against a sole supported on said pad, a heel abutment slidably carried by said member for movement toward and away from said pad, means operative in response to movement of said member in pressure-applying direction for locking said heel abutment to said member for movement therewith, means for releasing said locking means in response to movement of said member away from said pad, and means for urging said heel abutment away from said pad relative to said member.

7. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by the end of said rod adjacent to the pad, a collar adjustably carried by said rod and cooperating with said member for limiting the slideable movement of said rod relative to said member toward the pad, and means operative in response to movement of said member in pressure-applying direction for locking said rod to said member for movement therewith.

8. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said rod at the end adjacent to said pad, a spring urging said rod for slideable movement with respect to said member away from said pad, a collar adjustably carried by said rod and cooperating with said member for limiting movement of said rod with respect to said member toward the pad, means operative in response to movement of said member in pressure-applying direction for locking said rod to said member for movement therewith, and means for releasing said locking means in response to movement of said member in pressure-releasing direction whereby said spring is effective to move said rod relative to said member away from said pad.

9. In a machine for applying pressure to shoe parts, a pad for supporting a sole against which a shoe is to be pressed, a member for pressing a shoe against a sole supported on said pad, a rod slidably carried by said member for movement toward and from said pad, a heel abutment carried by said rod at the end adjacent to said pad, a pawl connected to said member and arranged when moved in one direction to lock said rod to said member for movement therewith, a spring tending to move said pawl into locking position, means for holding said pawl out of locking position, and means for releasing said holding means to permit movement of said pawl into locking position upon initial movement of said member in pressure-applying direction.

10. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said rod at the end adjacent to said pad, said rod being provided with rack teeth extending along the length thereof, a gear carried by said member, said gear being engageable with said rack teeth, means for rotating said gear to move said rod relative to said member, a spring acting to move said rod relative to said member

away from said pad, and means operative in response to movement of said member in pressure-applying direction to lock said rod to said member for movement therewith.

11. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said member at the end adjacent to said pad, a spring connected to said rod and arranged to move said rod relatively to said member away from said pad, said rod being provided with rack teeth, a gear connected to said member, said gear being engageable with said rack teeth and arranged upon rotation thereof to cause said rod to move toward said pad against the action of said spring, and a collar adjustably carried by said rod and cooperating with said member to limit movement of said rod by said gear toward said pad.

12. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said member at the end adjacent to said pad, a spring connected to said rod and arranged to move said rod relative to said member away from said pad, said rod being provided with rack teeth, a gear connected to said member, said gear being engageable with said rack teeth and arranged upon rotation thereof to cause said rod to move toward said pad against the action of said spring, a collar adjustably carried by said rod and cooperating with said member to limit movement of said rod by said gear toward said pad, and means operative in response to movement of said member in pressure-applying direction to lock said rod to said member for movement therewith.

13. In a machine for applying pressure to shoe parts, a pad for supporting a sole against which a shoe is to be pressed, a member for pressing a shoe against a sole supported on said pad, a heel abutment slidably carried by said member for movement toward and away from said pad, means supporting said member for bodily movement from a position in which the heel abutment is positioned directly over said pad to a position in which the heel abutment is out of vertical alignment with said pad, a handle by means of which said member is moved into a position in which the heel abutment is positioned directly over said pad, and means for moving said heel abutment vertically with respect to said member and said pad, said means including an actuating member positioned sufficiently close to said handle to be engaged by the thumb of the hand of the operator, the fingers of which are simultaneously grasping said handle.

14. In a machine for applying pressure to shoe parts, a pad for supporting a sole against which a shoe is to be pressed, a member for pressing a shoe against a sole supported on said pad, a heel

5 abutment slidably carried by said member for movement toward and away from said pad, a toe abutment for engaging the toe of a shoe supported on said pad, means for adjusting said toe abutment longitudinally of the pad, said means including an actuating handle adapted to be gripped by the fingers of a hand of the operator, and means for moving said heel abutment vertically with respect to said member, said means including an actuating member positioned sufficiently close to said handle to be engaged by the thumb of the hand of the operator while the fingers thereof are grasping said handle.

15. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said member at the end adjacent to said pad, a spring connected to said rod and arranged to move said rod relative to said member away from said pad, said rod being provided with rack teeth, a gear connected to said member, said gear being engageable with said rack teeth and arranged upon rotation thereof to cause said rod to move toward said pad against the action of said spring, a collar adjustably carried by said rod and cooperating with said member to limit movement of said rod by said gear toward said pad, means operative in response to movement of said member in pressure-applying direction to lock said rod to said member for movement therewith, and means for releasing said locking means in response to movement of said member in pressure-releasing direction.

16. In a machine for applying pressure to shoe parts, a pad for supporting a sole against which a shoe is to be pressed, a member for pressing a shoe against a sole supported on said pad, a rod slidably carried by said member for movement toward and away from said pad, a heel abutment carried by said member at the end adjacent to said pad, a spring connected to said rod and arranged to move said rod relative to said member away from said pad, said rod being provided with rack teeth, a gear connected to said member, said gear being engageable with said rack teeth and arranged upon rotation thereof to cause said rod to move toward said pad against the action of said spring, a collar adjustably carried by said rod and cooperating with said member to limit movement of said rod by said gear toward said pad, said rod being provided with ratchet teeth, a pawl connected to said member and arranged upon movement of said pawl to one position to engage said ratchet teeth to lock said rod for movement with said member, a spring urging said pawl into said one position, means for holding said pawl out of said position, and means carried by said member for releasing said holding means to permit movement of said pawl to said one position in response to initial movement of said member in pressure-applying direction.

CHARLES J. GROSS.
